MEAT MOLD

Jack Lebovitz, Pittsburgh, Pa., assignor, by mesne assignments, to C. E. Dippel & Company, New York, N. Y.

Application June 22, 1949, Serial No. 3,451

Term of patent 3½ years

(Cl. D44—29)

To all whom it may concern:

Be it known that I, Jack Lebovitz, a citizen of the United States, residing at 1524 Asbury Place, Pittsburgh, county of Allegheny, and State of Pennsylvania, have invented a new, original, and ornamental Design for a Meat Mold, of which the following is a specification, reference being had to the accompanying drawing, forming part thereof.

Fig. 1 is a top plan view of a meat mold, showing my new design;

Fig. 2 is a side elevational view;

Fig. 3 is a side elevational view thereof in an exploded position;

Fig. 4 is an end elevational view thereof, looking from the left side of Fig. 2;

Fig. 5 is a cross-sectional view thereof taken along line 5—5 on Fig. 2.

I claim:

The ornamental design for a meat mold, substantially as shown.

JACK LEBOVITZ.
